UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN FIXTURE.

Application filed March 8, 1926. Serial No. 93,002.

This invention relates to household fixtures employed to support curtains, portières, drapes, and the like, and has reference more especially to that type of fixture wherein the curtain, portière or drape is suspended from the rod or pole by a series of rings or other carriers slidably mounted on the rod or pole, and generally known as draw curtains.

Draw curtain fixtures are commonly equipped with pull cords that are connected to the inner or central carriers, in case of double or divided curtains, and to one of the end carriers in the case of a single curtain, and are trained over suitable guide pulleys at the ends of the rod or pole, to effect the drawing of the curtain or portière to open and closed positions. These draw cords and their supporting and guiding devices constitute a considerable part of the total cost of the fixture, and furthermore are unsightly and more or less in the way. An important object of the present invention is to simplify and improve curtain fixtures of this general type by doing away entirely with the pull cords and their accessories, and substituting therefor a simple easily operated attachment or accessory by which the curtain or drape can be readily pushed open or drawn closed even when, as is usually the case, the rod or pole is considerably above the reach of the operator standing on the floor. Another object is to provide a curtain operating device which may be permanently attached to the curtain carrier or curtain or both, and shall be practically concealed from view;

Other objects and attendant advantages of the invention will be apparent to persons familiar with devices of this character from the following detailed description, when taken in connection with the accompanying drawing in which I have illustrated one practical and approved embodiment of the invention, and wherein—

Fig. 1 is a front elevation of my improved curtain fixture showing the upper edge portions of a pair of curtains suspended therefrom.

Fig. 2 is a front elevation of the left hand

portion of Fig. 1, showing the left hand curtain pushed to open position; 50

Fig. 3 is an enlarged rear elevation of a fragment of the curtain rod and one of the inner carriers or hangers thereon, showing one manner of attaching the curtain manipulating rod or bar to the carrier; 55

Fig. 4 is a cross-section on the line 4—4 of Fig. 3; and

Fig. 5 is an enlarged cross-section on the line 5—5 of Fig. 1. 60

Referring to the drawings, 10 and 11 designate respectively the inner and outer telescoping sections of a curtain rod of the well-known hollow flat type, and 12 designates brackets on which the elbow-shaped ends of the rod sections 10 and 11 are mounted and supported. 13 designates each of a pair of mating curtains, which are suspended at their upper ends from the curtain rod by means of oblong flat rings or hangers 14 which are formed with eyes 15 at their lower ends to which the upper edges of the curtains 13 are attached as by stitching 16. 70

In the structure herein illustrated, the hangers or carriers 14 are formed on their upper ends with shoes or skids 17 that slidably rest on the upper edge of the rod and are formed with longitudinally convex inner surfaces bearing on the rod, so that the said skids will readily mount and slide over the end of the outer rod section and, when the curtain is drawn to open position, will partially stack up on each other in the manner illustrated in Fig. 2. This feature forms in part the subject-matter of a former application heretofore filed by me on the 17th day of January, 1925, Serial No. 2,977, and forms no part of the present invention, for the carrying out of which any suitable or approved rings or other carriers may be used. 85

In accordance with my present invention I provide in or behind the upper portion of the inner edge of each curtain 13 a depending rod or bar, preferably of metal, that is attached at its upper end to the innermost curtain ring or carrier and depends to a position wherein its lower end is readily within the reach of a person standing on the floor; 90

so that, by grasping the lower end of said rod or bar, the ring or carrier to which the rod or bar is attached may be bodily pushed or drawn over the curtain rod, pushing the other carriers before it during the opening movement of the curtain and drawing them after it during the closing movement of the curtain. In the form of the invention herein illustrated, 18 designates a steel rod that is preferably encased in a hem 13' in the upper portion of the inner edge of each curtain. The upper end of this rod may be soldered or otherwise attached to the innermost curtain carrier or ring 14 so as to be either rigidly or flexibly connected to the latter. In the drawings I have shown the depending shank of the hanger apertured for the stitching of the curtain thereto, and the aperture or eye is formed by a punch, which extrudes the metal on one side of the eye in the form of a ring 19; and on the upper end of the rod 18 is formed an eye 20 which embraces the ring 19, this latter being preferably formed on the rear side of the shank of the carrier. The eye 20 having been fitted onto the ring 19, the latter is mashed or swaged down over the eye 20 thereby securely locking the rod to the hanger or carrier.

30 For the proper manipulation of the curtain in opening and closing the same, means must be provided for locking the upper end of the outer edge of the curtain against inward sliding movement along the rod. A simple detachable device for accomplishing this, which is best shown in Figs. 1 and 5, consists of an inverted U-shaped clamp 21 of spring metal which is caused to straddle and grip the curtain rod adjacent to the elbow bend of the latter, the lower ends of the clamp being outwardly splayed as shown at 21' in Fig. 5, and having a spread slightly in excess of the outside width of the hangers. The outermost hanger is located just in rear of said clamp, so that the spread ends of the latter act as stops to prevent the inward sliding of the outermost hanger when the curtain is drawn inwardly toward closed position.

50 The manner of manipulating the device will be readily apparent from the foregoing description of its structural features. Assuming that the curtains are in closed position as shown in Fig. 1 and it is desired to open them, the user merely grasps the lower ends of the rods 18 and by a quick deft outward push along the curtain rod, the entire series of hangers are moved along the latter, creating the usual folds in the curtain as shown in Fig. 2. To close the curtain the rods are grasped in the same manner and drawn or pushed inwardly until the inner edges of the curtain approximately meet, the stops at the outer ends of the rod detaining

the outermost hangers, and the remaining 65 hangers sliding over the rod under the pull of the upper edge of the curtain.

It will thus be seen that the device of the present invention renders wholly unnecessary the use of the usual draw cords with 70 their guiding and supporting accessories, and substitutes a very simple inexpensive manually operable device by which the sliding movements of the curtain can be effected with equal certainty and celerity by a person 75 standing on the floor. The rods or bars 18 may, of course, be of any length, depending on the height of the curtain rod above the floor, and while I have shown the rods disposed within a hem in the curtain, it is 80 manifest that they may be located behind the inner edge of the curtain and stitched or otherwise attached at one or more points to the latter, being in that case equally concealed, and operable in the manner described.

I have herein shown and described one very simple and practical embodiment of the principle of the invention, but it is manifest that the details may be variously modified 90 within the principle of the invention and without sacrificing any of the advantages thereof. For instance, the laterally shiftable curtain operating member may be a rod, bar or strip of any material either rigid 95 or flexible but sufficiently strong to push or draw the curtain under a lateral thrust of the hand applied to its lower end. Hence, I do not limit the invention to the specific embodiment thereof herein presented for 100 purposes of illustration, but reserve all such variations and modifications as fall within the spirit and purview of the appended claims.

105 I claim—

1. In a curtain fixture of the type having a curtain rod and a curtain suspended from the rod by hangers slideable on the rod, the combination with an end hanger, of a strip attached to an edge of the curtain beneath 110 said end hanger and extending to within reach of a person on the floor, said strip being sufficiently stiff to adapt it, by manual side thrust applied to the lower end thereof, to push and draw the hangers along the rod. 115

2. In a curtain fixture of the type having a curtain rod and a curtain suspended from the rod by hangers slideable on the rod, the combination with an end hanger, of a strip attached to said end hanger and extending 120 to within reach of a person on the floor, said strip being sufficiently stiff to adapt it, by manual side thrusts applied to the lower end thereof, to push and draw the hangers along the rod.

125 3. In a curtain fixture of the type having a curtain rod and a curtain suspended from the rod by hangers slideable on the rod, the

combination with an end hanger, of a strip attached to said end hanger and to the marginal portion of the curtain beneath said end hanger and extending to within reach of a person on the floor, said strip being sufficiently strong to push and draw the hangers over the rod under manual side thrusts applied to its lower end.

4. A specific embodiment of claim 2, wherein the hanger-operating strip is so disposed as to be concealed by the curtain. **10**

5. A specific embodiment of claim 2, wherein the hanger-operating strip consists of a rod enclosed in a hem on the edge of the curtain.

JAMES H. BOYE.
